(57) **CLAIM**

The ornamental design for a vehicle exterior, as shown and described.

DESCRIPTION

FIG. 1 is a top plan view of a vehicle exterior;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a front left perspective view thereof; and,

FIG. 7 is a rear left perspective view thereof.

The de-emphasized and halftone portions shown in the drawings illustrate portions of the vehicle exterior that forms no part of claimed design.
